Owen O. Hembree, San Gabriel, Calif.

Application December 23, 1944, Serial No. 117,062

Term of patent 14 years

(Cl. D52—1)

To all whom it may concern:

Be it known that I, Owen O. Hembree, a citizen of the United States, residing at San Gabriel, in the county of Los Angeles and State of California, have invented a new, original, and ornamental Design for a Palm Reading Scale, of which the following is a specification, reference being had to the accompanying drawing forming part thereof.

Fig. 1 is a front elevation of a palm reading scale embodying my new design.

Fig. 2 is a side elevation.

Fig. 3 is a rear elevation.

I claim:

The ornamental design for a palm reading scale, substantially as shown.

OWEN O. HEMBREE.
